CONTRAST EXPANSION CIRCUIT
ARRANGEMENT

Henricus Adrianus Broos, Eindhoven, Netherlands, assignor to Hartford National Bank and Trust Company, Hartford, Conn., as trustee

Application December 10, 1947, Serial No. 790,831
In the Netherlands September 13, 1946

4 Claims. (Cl. 179—171)

1

This invention relates to a further improvement in the invention described and claimed in my copending patent application, No. 661,520. In the said parent application, a contrast expansion circuit arrangement is described in which use is made of a discharge tube comprising at least a cathode, a first control-grid, a screen-grid, a second control-grid, a second screen-grid and an anode, the input voltage to be amplified being supplied to one or to either of the two control-grids, whereas a control-voltage derived from the amplitude of the amplified voltage (output voltage) is fed to the second control-grid, the circuit of the first and the second screen-grids, which are electrically interconnected, including an impedance which is so high for the frequency of the oscillations to be amplified that the slope of the characteristic curve indicating the anode current as a function of the input voltage is increased with increasing negative control-voltage.

According to the present invention this circuit-arrangement is improved by providing a positive feedback circuit between the anode and the first control-grid. The measure according to the present invention ensures considerably greater expansion of the input voltage to be amplified than the circuit-arrangement according to the copending patent application.

In order that the invention may be more clearly understood and readily carried into effect, it will now be described more fully with reference to the accompanying drawing, in which Figs. 1 and 2 show, by way of example, embodiments thereof.

In Fig. 1, the input voltage to be amplified is fed from the terminals 1 and 2 to a first control-grid 4 of a discharge tube 5. The amplified output voltage is abstracted from terminals 7 and 8 through a resistance 6 included in the anode circuit. Part of this voltage is rectified with the use of a rectifying tube 15 and fed, as the control voltage, to a second control-grid 11 of the discharge tube 5. The circuit connected to two screen-grids 10 and 12 includes a resistance 17 of such high value that the slope of the characteristic curve which shows the anode current as a function of the input voltage, is increased with increasing negative control voltage. A circuit-arrangement of this kind ensures contrast expansion of the voltage which is required to be amplified and fed to the input terminals 1 and 2, i. e. the ratio between the output voltage taken from the terminals 7 and 8 and the input voltage

2

fed to the terminals 1 and 2 is increased if the amplitude of these voltages increases.

According to the invention considerably greater contrast expansion is ensured by providing a feedback circuit producing a positive feedback between the anode 14 and the first control-grid 4 of the tube 5; this feedback circuit may comprise, for example, a blocking condenser 30 and a potentiometer 31, 32.

10 This may be appreciated as follows: owing to the resistance 17 in the circuit of the grids 10 and 12 the voltage of these grids is in phase opposition with the voltage of the first control-grid 4. Set up between the screen-grid 10 and the second control-grid 11 is thus a negative space charge which may be regarded as a virtual cathode. The part of the tube containing this virtual cathode, grid 12, and the anode operates as a pentode in which the anode current is controlled by the voltage on the grid 12, and the screen grid 10 can be considered as a space charge electrode. Thus the anode voltage is in phase opposition with the voltage at the grid 12, that is to say, it exhibits the same phase as the input voltage on the grid 4.

15 The provision of the circuit 30, 31, 32 thus results in a positive feedback, so that the voltages on the grids 4, 10 and 12 are higher than would be the case without this feedback. The control voltage fed to the second control-grid 11 controls the mutual conductance of the aforesaid pentode part of the tube 5. Since, however, the control voltage on the grid 12 of this pentode part exhibits a higher value than without feedback, a higher control voltage is set up and under the influence thereof the mutual conductance of this tube part is subjected to a greater variation with the result that greater contrast expansion is obtained.

20 25 30 35 40 Fig. 2 of the drawing shows a similar circuit-arrangement in which the input voltage is fed to the second control-grid 11. Also in this embodiment the provision of a feedback circuit 30, 31, 32 which brings about a positive feedback results in considerable increase in contrast expansion of the input voltage.

45 What I claim is:

1. An amplifier circuit arrangement for expanding the amplitude of an electrical oscillation, comprising an electron discharge tube having a cathode, a first control grid, a first screen grid, a second control grid, a second screen grid and an anode, said tube having a characteristic wherein for a predetermined value of operating potential on said first and second screen grids

relative to the potentials on the other elements of said tube the mutual conductance of the tube as represented by the anode current-control grid voltage ratio increases with an arithmetic decrease of the control voltage, means including a resistor common to said first and said second screen grids to apply operating potentials to said electron discharge tube, means to apply said oscillation to one of said control grids, means to derive a control voltage proportional to the amplitude of said oscillation including a rectifying device having a cathode and having an anode coupled to the anode of said tube, means intercoupling the cathode of said rectifying device and the cathode of said tube and maintaining a substantially constant potential relationship therebetween, means to apply said voltage to said second control grid, said resistor having a resistance value at which the potential applied to said first and second screen grids is substantially equal to said predetermined value of operating potential, and network means intercoupling the anode of said discharge tube and the first control grid of said discharge tube in regenerative relationship at the frequency of said oscillation.

2. An amplifier circuit arrangement for expanding the amplitude of an electrical oscillation, comprising an electron discharge tube having a cathode, a first control grid, a first screen grid, a second control grid, a second screen grid and an anode, said tube having a characteristic wherein for a predetermined value of operating potential on said first and second screen grids relative to the potentials on the other elements of said tube the mutual conductance of the tube as represented by the anode current-control grid voltage ratio increases with an arithmetic decrease of the control voltage, means including a resistor common to said first and said second screen grids to apply operating potentials to said electron discharge tube, means to apply said oscillation to said first control grid, means to derive a control voltage proportional to the amplitude of said oscillation including a rectifying device having a cathode and having an anode coupled to the anode of said tube, means intercoupling the cathode of said rectifying device and the cathode of said tube and maintaining a substantially constant potential relationship therebetween, means to apply said voltage to said second control grid, said resistor having a resistance value at which the potential applied to said first and second screen grids is substantially equal to said predetermined value of operating potential, and network means comprising a series circuit including a resistive element and a capacitive element intercoupling the anode of said discharge tube and the first control grid of said discharge tube in regenerative relationship at the frequency of said oscillation.

3. An amplifier circuit arrangement for expanding the amplitude of an electrical oscillation, comprising an electron discharge tube having a cathode, a first control grid, a first screen grid, a second control grid, a second screen grid and an anode, said tube having a characteristic wherein for a predetermined value of operating potential on said first and second screen grids relative to the potentials on the other elements of said tube the mutual conductance of the tube as represented by the anode current-control grid

voltage ratio increases with an arithmetic decrease of the control voltage, means including a resistor common to said first and said second screen grids to apply operating potentials to said electron discharge tube, means to apply said oscillation to said second control grid, means to derive a control voltage proportional to the amplitude of said oscillation including a rectifying device having a cathode and having an anode coupled to the anode of said tube, means intercoupling the cathode of said rectifying device and the cathode of said tube and maintaining a substantially constant potential relationship therebetween, means to apply said voltage to said second control grid, said resistor having a resistance value at which the potential applied to said first and second screen grids is substantially equal to said predetermined value of operating potential, and network means comprising a series circuit including a resistive element and a capacitive element intercoupling the anode of said discharge tube and the first control grid of said discharge tube in regenerative relationship at the frequency of said oscillation.

4. An amplifier circuit arrangement for expanding the amplitude of an electrical oscillation, comprising an electron discharge tube having a cathode, a first control grid, a first screen grid, a second control grid, a second screen grid and an anode, said tube having a characteristic wherein for a predetermined value of operating potential on said first and second screen grids relative to the potentials on the other elements of said tube the mutual conductance of the tube as represented by the anode current-control grid voltage ratio increases with an arithmetic decrease of the control voltage, means including a resistor common to said first and said second screen grids to apply operating potentials to said electron discharge tube, means to apply said oscillation to one of said control grids, means to derive a control voltage proportional to the amplitude of said oscillation including a rectifying device having a cathode connected in common with the cathode of said tube and having an anode coupled to the anode of said tube, means to apply said voltage to said second control grid, said resistor having a resistance value at which the potential applied to said first and second screen grids is substantially equal to said predetermined value of operating potential, and network means comprising a series circuit including a resistive element and a capacitive element intercoupling the anode of said discharge tube and the first control grid of said discharge tube in regenerative relationship at the frequency of said oscillation.
